(57) **CLAIM**

The ornamental design for a power and data center, as shown and described.

DESCRIPTION

FIG. 1 is a top perspective view of a power and data center showing our new design in a partial-open configuration;

FIG. 2 is another top perspective view thereof;

FIG. 3 is a bottom perspective view thereof;

FIG. 4 is another bottom perspective view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a left elevation view thereof;

FIG. 10 is a right elevation view thereof;

FIG. 11 is a top perspective view of the power and data center in a closed configuration;

FIG. 12 is another top perspective view thereof;

FIG. 13 is a bottom perspective view thereof;

FIG. 14 is another bottom perspective view thereof;

FIG. 15 is a top plan view thereof;

FIG. 16 is a bottom plan view thereof;

FIG. 17 is a front elevation view thereof;

FIG. 18 is a rear elevation view thereof;

FIG. 19 is a left elevation view thereof;

FIG. 20 is a right elevation view thereof;

FIG. 21 is a top perspective view of another power and data center showing our new design in a partial-open configuration;

FIG. 22 is another top perspective view thereof;

FIG. 23 is a bottom perspective view thereof;

(Continued)

FIG. 24 is another bottom perspective view thereof;
 FIG. 25 is a top plan view thereof;
 FIG. 26 is a bottom plan view thereof;
 FIG. 27 is a front elevation view thereof;
 FIG. 28 is a rear elevation view thereof;
 FIG. 29 is a left elevation view thereof;
 FIG. 30 is a right elevation view thereof;
 FIG. 31 is a top perspective view of the power and data center of FIG. 21 in a closed configuration;
 FIG. 32 is another top perspective view thereof;
 FIG. 33 is a bottom perspective view thereof;
 FIG. 34 is another bottom perspective view thereof;
 FIG. 35 is a top plan view thereof;
 FIG. 36 is a bottom plan view thereof;
 FIG. 37 is a front elevation view thereof;
 FIG. 38 is a rear elevation view thereof;
 FIG. 39 is a left elevation view thereof; and,
 FIG. 40 is a right elevation view thereof.

The broken lines in the Figures are for the purpose of illustrating portions of the power and data center that form no part of the claimed design.

1 Claim, 40 Drawing Sheets
